UNITED STATES PATENT OFFICE

2,613,123

FROZEN FOOD DRAWER FOR
REFRIGERATORS

Ray E. Patten, deceased, late of Westport, Conn.,
by Carl L. De Pue, executor, Westport, Conn.,
assignor to General Electric Company, a corpora-
tion of New York

Application April 16, 1949, Serial No. 87,984

1 Claim. (Cl. 312—214)

1

This invention relates to a refrigerator cabinet and more particularly to a refrigerator cabinet including a drawer for frozen food.

For convenience of access, it is sometimes desirable to store frozen food in a drawer which may be moved into and out of a compartment which is maintained about 0° F. However, such an arrangement involves the difficulty that frost may form on the sliding surfaces and make the drawer difficult to slide.

Accordingly, it is an object of this invention to provide a drawer for frozen food including an arrangement for positioning the sliding surfaces so as to minimize frost formation thereon.

Further objects and advantages of this invention will become apparent as the following description proceeds and the features of novelty which characterize this invention will be pointed out with particularity in the claim annexed to and forming part of this specification.

In carrying out this invention the sliding surfaces of a frozen food storage drawer are arranged in regions where the temperature is well above the temperature maintained in the drawer itself. In one embodiment the sliding surfaces are located in the machinery space and in another embodiment the sliding surfaces are located within the insulation space of the cabinet.

For a better understanding of this invention reference may be had to the accompanying drawings in which Fig. 1 is a front elevation view, partly broken away, of a portion of a refrigerator embodying this invention; Fig. 2 is a sectional elevation view taken along the lines 2—2 of Fig. 1; Fig. 3 is an enlarged sectional view of a portion of Fig. 2; Fig. 4 is a sectional view taken along the lines 4—4 of Fig. 3; Fig. 5 is a front elevation view, partly broken away, of a portion of a refrigerator showing a modified form of this invention; Fig. 6 is a sectional elevation view taken along the lines 6—6 of Fig. 5; Fig. 7 is a sectional plan view taken along the lines 7—7 of Fig. 5; Fig. 8 is an enlarged view, partly broken away, showing a detail of the construction; and Fig. 9 is a sectional view taken along the line 9—9 of Fig. 8.

Referring now to Figs. 1 and 2, there is shown a refrigerator cabinet 1 including an outer metal wall or case 2 and a plurality of spaced inner walls or liners 3 and 4. The space between the outer wall and the liners is filled with a suitable heat-insulating material 5. The liner 3 forms a compartment 3' for receiving a sliding drawer 6 for the storage of frozen foods. The liner 4 forms a compartment 7 for the storage of fresh

2

foods. The access opening of the compartment 7 is closed by a door 8 and the access opening of the compartment 3' is closed by the front vertical portion 9 of the drawer 6. A gasket 10 is provided on the portion 9 of the drawer for engaging the face 11 of the cabinet, and a latch 12 is provided at each side of the portion 9 of the drawer. The latches 12 are actuated by a handle 13, and each engages a strike one of which is indicated by 14. The handle is also utilized for moving the drawer to its open and closed positions.

In the lower portion of the cabinet there is provided a machinery compartment 15 for housing the condensing unit of the refrigerating system. In order to refrigerate the compartment 3' and hence the contents of the drawer 6 an evaporator 16 in the form of a plurality of turns of tubing is secured to the exterior of the liner 3. Condensing apparatus including a hermetically sealed motor-compressor unit 17 and a condenser 18 is housed within the machinery compartment 15. Liquid refrigerant is supplied from the condensing unit to the evaporator 16 through a capillary tube 19, and vaporized refrigerant is withdrawn from the evaporator through a suction line 20. The compartment 7 for the storage of fresh food may be refrigerated in any desired manner, either by separate apparatus or by an evaporator supplied from the same condensing unit as is used to refrigerate the frozen food compartment 3'.

In order to properly preserve the frozen food the compartment 3' is normally maintained at a temperature in the neighborhood of zero degrees F. At such a temperature frost forms on the interior of the liner 3 and, should the drawer 6 be supported for sliding motion on rails located within the compartment 3', the frost would ultimately render movement of the drawer exceedingly difficult or impossible. In order to overcome this difficulty, an arrangement has been provided whereby the drawer is supported for sliding movement on rails positioned within the machinery compartment 15. As shown in Fig. 2, the drawer 6 is supported in spaced relationship to the liner 3 and hence a substantial amount of frost can form on the interior of the liner without interference with the movement of the drawer.

Referring now also to Figs. 3 and 4, a plurality of brackets 21 are secured, as by welding, to the bottom surface of the outer wall of the refrigerator in the upper region of the machinery compartment 15. Two such brackets are located

near each side of the refrigerator, one in the forward portion and the other in the rearward portion of the machinery compartment. A rail or channel 22 is mounted on each pair of supporting brackets 21 and extends from the front to the rear of the machinery compartment. In order to mount the drawer for sliding movement along the channels 22 the drawer is provided with two L-shaped members 23. Each of the members 23 is secured to a metal wall 24 of the front portion 9 of the drawer. The members 23 may be secured to the wall 24 in any suitable manner, as by welding, at the points 25, 26, and 27. In order to facilitate free movement of the drawer each of the members 23 is provided at the rear of its horizontal leg 28 with a roller 29. These rollers are adapted to ride within the channels 22. A second roller 30 is mounted on each of the channels 22 near the front edge thereof and the lower surfaces of the members 23 are adapted to ride on the rollers 30. The rear end of each of the channels 22 is inclined, as indicated at 31, to assist in moving the drawer to its closed position.

It can be seen that the surfaces where the relative motion between the drawer and its stationary supports takes place are located within the machinery compartment 15 where the temperature is well above freezing, and hence there is no tendency for frost to form on these surfaces and to hamper the operation of the drawer.

A modified form of this invention showing a different arrangement for slidably supporting the drawer is illustrated in Figs. 5 through 9. The construction is similar to that shown in Figs. 1 through 4, and corresponding parts have been designated by the same numerals. In the form shown in Figs. 5 through 9 the drawer is mounted for sliding movement along two rails or channels 22'. These channels extend horizontally from the front to the rear of the cabinet, one of the channels being arranged at each side of the cabinet. As shown most clearly in Fig. 9 each of the channels 22' is secured, by welding or in any other suitable manner, to the outer wall 2 of the cabinet. In order to support the drawer for sliding movement along the channels and in spaced relationship to the inner liner 3 of the frozen food compartment, a U-shaped member 32 is employed. The member 32 is secured to the wall 24 of the portion 9 of the drawer in any suitable manner, as by welding at the points indicated by 33 and 34 in Fig. 7. A roller 29' is mounted at the rear end of each arm 35 of the U-shaped member 32, and these rollers are adapted to be received within the channels 22'. A roller 30' is mounted at the forward end of each of the channels 22' to further facilitate easy movement of the drawer to and from its closed position. Each of the channels 22' is inclined at its rear end, as indicated by 31', to assist in moving the drawer to its closed position.

Each sliding assembly including a channel 22', rollers 29' and 30', and an arm 35 of the member 32 is enclosed within a space formed by an elongated member 36 of U-shaped cross section. As shown most clearly in Fig. 9 this member 36 includes flanged portions 37 and 38 which are secured in any suitable manner, as by welding, to the interior of the outer wall 2 of the refrigerator. The elongated member 36 extends from the front to the rear of the refrigerator and is adapted to be secured to the back portion 39 of the outer wall 2 of the refrigerator in any

suitable manner, as by welding, along a line indicated by 40 in Fig. 7. If desired, the member 36 may also be flanged adjacent the rear wall portion 39 to facilitate welding it to the rear wall. The forward end of the member 36 is similarly secured to a portion 41 of the outer wall of the refrigerator, as indicated by 42. The member 36 forms an enclosure for the various parts of the sliding assembly and prevents the heat-insulating material 5 from finding its way into the mechanism. Further, since this member is sealed to the outer wall 2 of the cabinet it minimizes the entrance into the insulation of moisture which might otherwise pass through the opening provided in the front of the refrigerator for receiving the sliding member 32.

It can be seen that the compartment 43 formed by the elongated member 36 is spaced from the liner 3 of the frozen food compartment and this space is filled with heat-insulating material 5. Furthermore, the coils which make up the evaporator 16 are arranged along the top, back and bottom of the exterior of the liner 3 and do not extend along the sides into the space between the liner 3 and the compartment 43. Moreover, this compartment is immediately adjacent the outer wall of the refrigerator. Thus the temperature within the compartment 43 is normally above 32 degrees F. and any tendency toward the formation of frost on the relatively movable portions of the mechanism arranged therein is minimized. The rails or channels 22' are secured directly to the outer wall of the refrigerator, and this further minimizes any tendency for frost to form on the surfaces of the rails.

While specific embodiments of this invention as applied to a frozen food drawer of a combination refrigerator have been shown and described, it is not desired that this invention be limited to the particular constructions shown and described, and it is intended, by the appended claim, to cover all modifications within the spirit and scope of this invention.

What this invention claims as new and desires to secure by Letters Patent of the United States is:

A refrigerator cabinet including an outer case, a spaced inner wall formed to provide a compartment, means for refrigerating said compartment, a machinery compartment, a drawer adapted to move horizontally within said first-named compartment in spaced relationship thereto, horizontal supports mounted in said machinery compartment, and a plurality of L-shaped brackets fixedly secured to said drawer, each of said brackets having one leg extending into said machinery compartment and into sliding engagement with one of said horizontal supports for slidably maintaining said drawer horizontal and in spaced relationship to said inner wall.

CARL L. DE PUE,
Executor of the Estate of Ray E. Patten, Deceased.
